UNITED STATES PATENT OFFICE.

JOHN H. WILSON, OF NEW KENSINGTON, PENNSYLVANIA, ASSIGNOR TO THE ALUMINUM COMPANY OF AMERICA, OF PITTSBURGH, PENNSYLVANIA.

COMBINED WRAPPER AND CATALOGUE.

Application filed March 22, 1926. Serial No. 96,594.

This invention relates to a combined wrapper and catalogue for use in wrapping merchandise.

It is the practice in some industries as, for example, that pertaining to the manufacture of aluminum cooking utensils, to attach to each utensil a small catalogue in the form of a booklet in which are printed pictures and descriptions of different articles made and sold by the company from which the particular utensil is procured. Thereafter the utensil, with the catalogue attached thereto, has been carefully wrapped to provide a protection for the utensil while handled. It has been found, however, that 90% of all purchasers of the utensils, after unwrapping the same, tear the catalogue from the utensil and discard it without glancing at its contents. The remaining 10% or less of the purchasers will read the catalogues but it is questionable whether the expense incident to the production and attaching of the catalogues is justified by the business resulting from the use of the catalogue although it is known that this catalogue does create some new business.

It is an object of the present invention to dispense with the printing of the catalogues and yet present to the customer in a satisfactory manner the line of goods sold by the manufacturer so that the same advantages are obtained as though a catalogue had been used without, however, entailing the cost of the catalogue.

With this end in view the invention resides in the provision of a wrapper on which the various articles produced and sold by the particular company are illustrated and described, the wrapper being divided into opposed groups, and reading matter in one group being disposed oppositely to the reading matter in the other group so that when the wrapper is placed about an article and secured the exposed data thereon can be read easily no matter which side or end is in view, thus tending to attract the notice of the observer to one or more items made and sold by the manufacturer of the particular goods in the package.

The invention also consists in certain other novel details of a wrapper as hereinafter more fully described and pointed out in the claim, it being understood that various changes may be made therein without de-

parting from the spirit or sacrificing any of 55 the advantages of the invention as claimed.

In the accompanying drawings the preferred form of the invention has been shown.

In said drawings,

Figure 1 is a perspective view of a package provided with a wrapper such as constitutes the present invention, the package being shown on one side with the bottom, top and one end portion exposed.

Figure 2 is a plan view of the complete 65 wrapper on a reduced scale.

Referring to the figures by characters of reference 1 designates a sheet of wrapping paper on which are printed two groups of descriptions, etc., indicated at 2 and 3 respectively. The printed matter is so displayed on the sheet 1 that the subject matter of each group forms a page the bottom of which is a line extended transversely of the sheet at the center thereof, indicated at 4. When it is 70 desired to wrap a package, the sheet 1 is placed with its printed face downward and the article to be wrapped is placed on the middle portion of the sheet. Said sheet is then folded upwardly around the sides and 75 ends and onto the top of the package and fastened by any suitable means. Consequently the printed matter of the two groups 2 and 3 can be conveniently read from any 80 side of the package and will more readily 85 attract notice of an observer than would a wrapper containing printed matter all of which would be readable from one end of the sheet, as in a newspaper. With such an arrangement, when the package is wrapped, 90 some of the items would be up-side-down and could not be read conveniently. With the present arrangement, however, when the wrapped package is placed on a shelf it is possible for the observer to read items at all 95 sides thereof. When the package is unwrapped the same information is given to the customer as is afforded by the use of a small catalogue such as heretofore referred to and it has been found that the same percentage of wrappers will be read as has been of the small catalogues formerly used. Thus at a much less expense the advertising features of the package are retained without 100 sacrificing any of the advantages present in 105 the packages commonly used. As a matter of fact the package is rendered more attractive by the use of a wrapper such as de-

scribed and has been more efficient as an advertising medium than a package in a plain wrapper containing a catalogue which is attached to the wrapped article.

5 What is claimed is:

A sheet of paper to be used as a wrapper for packages having printed thereon two

groups of advertising matter the printing of one of the said groups being reversed relatively to the other.

In testimony that I claim the foregoing as my own, I have hereto affixed my signature.

JOHN H. WILSON.
